CAISSON

Charles Goodman, New York, N. Y.

Application December 19, 1947, Serial No. 792,752

1 Claim. (Cl. 61—81)

I
This invention relates to sub-aqueous constructions, and has for its main object to provide novel and more efficient methods and means for exploring, testing, and removing material in underwater operations than is the case with the methods and means now in use for the same.

My invention particularly aims to improve the operations for sinking and constructing caissons and to provide novel methods and means to reduce the resistance encountered in sinking caissons, and to facilitate the removal of material from underneath and inside of the caisson.

Still a further object of my invention is to provide means for making it possible for workmen to remain longer in sub-aqueous compressed air working chambers, and to operate in any kind of working chambers under water set much deeper than has been the case heretofore.

Still another object of my invention is to provide methods and means whereby workmen in sub-aqueous working chambers may explore, test, operate on, and remove material outside of the working chamber from the inside thereof.

Further objects of this invention will be apparent as the specification of the same proceeds or will be pointed out therein.

In the drawings forming a part of this specification and accompanying the same:

Fig. 1 is a diagrammatic plan view of a caisson as it is built today, and

Fig. 2 is a sectional view of one form thereof, while

Fig. 3 is a diagrammatic sectional view in another form;

Fig. 4 is a diagrammatic plan view of one form of a caisson built according to my invention, and

Fig. 5 is a diagrammatic sectional view thereof as indicated by the line 5—5 in Fig. 4;

Fig. 6 is a fragmentary diagrammatic plan view of a modified form of a caisson built according to my invention, and

Fig. 7 is a sectional view thereof as indicated by the line 7—7 of Fig. 6;

Fig. 8 is a fragmentary diagrammatic plan view of a modification of the caisson indicated in Fig. 6;

Fig. 9 is a fragmentary sectional view of an atmospheric or free air working chamber placed underneath the caisson walls, built according to the form of my invention indicated in Figs. 6 and 7, the same being shown on a larger scale than that of the diagrams of said figures;

Fig. 10 shows a modification of a valve and stuffing box construction used in Fig. 9, and

Fig. 11 indicates the use of such a valve for

observation through the walls of a sub-aqueous chamber.

Fig. 12 is a sectional view of a circular smaller caisson or shaft being sunk according to my novel method and construction, and

Fig. 13 is a sectional view thereof, the section being taken on the line 13—13 of Fig. 12.

My invention will be described and explained as applied to constructing and sinking caissons, and other uses thereof or sub-combinations of the same will be apparent or will be pointed out.

Caissons may be classified into two general types: open dredged caissons and compressed air caissons. All caissons (whether rectangular or circular) are built of a size or shape depending on the needs of the project involved, whether it be for a bridge foundation or open shaft such as the areaways used for ventilation shafts in underwater tunnels. In Fig. 1 I illustrate a rectangular caisson 20, possibly braced with center struts 21, as one of the more common types of caissons now being used in daily practice. Such a caisson is usually constructed of steel, wood or concrete or any combination of similar materials.

Its height 22 above river or ground water is determined by the nature of the end structure required. The thickness of its walls 23 is determined by the intensity of the forces developed during sinking as well as the hydrostatic and material pressures exerted on the structure under all conditions. The center struts 21 are used to prevent collapse of the longer side under these pressures. Of course if the caisson were circular or of a smaller rectangle or square, a center strut may not be required, as is often the case. The cutting edge 24 of a caisson is made in many shapes, one type of which is shown Figs. 2 and 3. The walls of the caisson are usually filled with concrete 25 to give it the weight required for sinking and the solidity required for the usual foundation.

A caisson is sunk through ground and water by removing material from within its perimeter through the dredge wells 26, 27 and 28, thereby undermining the walls of the caisson and allowing the structure to sink into the excavation which has been dug in this manner. The method used to excavate within the caisson has determined its classification heretofore whether it be an open dredged or compressed air caisson.

In the compressed air caisson a roof 29 (Fig. 3) is placed over each of the dredge wells 26, 27 and 28, thereby forming the usual working chamber 30 over the entire bottom area of the caisson. Access to this working chamber 30 is made

through the air lock 31 and the connecting shaftway 32. With such a compressed air chamber men with their tools enter and leave through the locks 31.

Excavation of the bottom is done by these men under air pressure and all the material is likewise removed through the locks 31 and shaftways 32 provided by means of buckets or similar devices which are loaded by the men in the working chamber 30. Of course, the working chamber 30 is placed under sufficient air pressure to balance the hydrostatic head 33 and thereby keep the excavation dry so that men can work at the bottom.

In the open dredged caisson the entire dredge wells 26, 27 and 28 are left completely open (Fig. 2). Excavation is carried on from above, usually by means of grab buckets 34. Material is removed from within the caisson directly through the water 35 which will fill the dredge wells as the excavation progresses and the caisson sinks.

Both methods now in use have advantages and disadvantages, and my invention combines their advantages and eliminates the disadvantages, as will be shown presently.

The resistance encountered in sinking a caisson is due to three separate and distinct forces:

(a) The frictional resistance of the vertical sides.

(b) The force of buoyancy due to its water displacement and, when air pressure is used, the pressure of the compressed air on the projected area of the working chamber.

(c) Bearing of the bottom of the wall on the unexcavated material.

In the compressed air caisson men are able to work directly under the cutting edge and remove all material under the wall perimeter and thus effectively remove the force of bearing from inhibiting the sinking of the caisson. This is not possible in the open dredged caisson as excavation from above can only be done within the area of the dredge wells 26, 27 and 28, making it necessary to dig as close as possible to the walls of the dredge well within the limitation of the size of the excavation tool operated from above.

Since in the compressed air caisson men have direct access to the material they are digging, it is easier to dig hard materials such as consolidated clay and hardpan with boulders than it is with the grab bucket or any other surface excavating tool. Since access to the bottom is available, it is therefore easier to keep proper line and grade of the compressed air caisson by controlled digging at the spot.

However, the compressed air caisson has a much greater uplift due to the force of buoyancy of the air pressure over the entire projected area of the caisson than the open dredged caisson which has a net uplift due only to the displacement of its walls. In large caissons, the open dredged caissons represent as much as 60% to 75% decrease in uplift forces over the compressed air caisson. With an open dredged caisson it is also possible to pump the water out of the dredge wells to a lower level, thus decreasing the displacement of the walls and in this manner decreasing the buoyancy still further.

The open dredged caisson can be sunk to greater depths than the compressed air caisson since there is a limit to the air pressures that men can work under (50 lbs. per square inch or approximately 115 ft. of water). Since no men work at the bottom the open caisson can be sunk to any depth required provided the bucket

can continue to excavate the material at the greater depths.

The main advantage of the open dredged caisson is the fact that material is removed quickly and efficiently without the tedious procedure of passing through air locks. This is often the deciding factor in the choice of this method.

My invention will provide direct access to the cutting edge for men and tools to eliminate bearing resistance without the increase in buoyancy inherent in the above described compressed air method. It will permit the caisson to be sunk to any depths unlimited by safe air pressures of the compressed air caisson and still provide access to the cutting edge to men and tools at this greater depth. The use of my method combines all the virtues of the compressed air method together with the prime virtue of the open dredge method of using the bucket without the necessity of removing excavated material through air or muck locks.

In addition my invention provides for positive means of reducing the skin friction against the sides of the caisson which neither the open dredge nor compressed air method can do.

In brief, my invention reduces skin friction, buoyancy and bearing resistance to an absolute minimum, which heretofore has never been done in one combination.

To illustrate my novel constructions and method to be used in the sinking of caissons Figs. 4 to 8 show plan and sectional views of caissons similar in size and shape to that of Figs. 1, 2 and 3 but which incorporate my novel cutting edge working chamber, generally indicated by the numerals 36 and 36a in its two respective modifications.

To illustrate first my compressed air cutting edge working chamber and the methods involved in using it and referring to Figs. 4 and 5, 37 is the outer skin wall of the caisson and also the external wall of the cutting edge working chamber 36, and 38 is the inner skin wall of the caisson and the inner wall of the cutting edge working chamber. As will be seen the working chamber 36 is confined to the perimeter of the caisson walls only. The roof 39 of the working chamber is at the same time the lower limits of the concrete filled walls 40. The struts 21 (Fig. 4) are the same as in Fig. 1 and they are above my cutting edge working chamber 36. The dredge wells 26, 27 and 28 also are the same as in Figs. 1 and 2.

Referring to Fig. 5, 41 is an access shaft to the cutting edge working chamber 36, and 42 is the air lock through which men and tools can enter and leave the working chamber. It can be seen, that, since the working chamber 36 is directly beneath the walled perimeter of the caisson and approximately the same width as the concrete filled walls thereof, the air lock 42 and connecting shaftway 41 are within the confines of the concrete filled walls 40. The dredge wells 26, 27 and 28 are left completely open to the access of a grab bucket or other excavating tool while the area beneath the caisson walls and along the cutting edge are directly accessible to men and tools. With this construction sinking is performed in the following manner. Excavation of the material is done from above by the grab buckets 34, or similar tools, directly through the water which is shown at a level 43 above the internal edge 44 of the working chamber. This dredging through the water covers the entire

5

area of the dredge wells. Men with their tools enter the cutting edge working chamber 36 through the air locks 42 and access shaftways 44 and dig the material at the cutting edge and beneath the caisson walls. The working chamber 36 is kept under an air pressure sufficient to balance the internal hydrostatic head 43 within the dredge wells. The material dug by the men in the working chamber 36 is not removed through the shaftways and air locks as now is the case with caissons of the type of Fig. 3, but is pushed under the bottom edge 44 of the inner wall 38, directly into the dredge wells 26, 27 and 28 where this loosened material is readily grabbed by the buckets 34 and removed to the surface. Powerful water or air jets indicated at 45, may be used as an aid to wash this loosened material to a location convenient for removal by the surface excavating tools. Fig. 5 shows the bottom edge 46 of the outer wall 37 lower than the inner bottom edge 44, so that the outer edge will always be buried in the bottom material as a seal to the outside, while the material from under the caisson wall is being shoved into the dredging wells. Of course, this leading edge is to be adjusted to a height depending on the material expected to be encountered and in many cases it would be just as feasible to have edges 44 and 46 at the same elevation.

Should the material be of a hard nature, such as the consolidated clays or hardpan with boulders, as mentioned above, so that it is difficult, if not impossible, to dig it in its natural state with a surface excavating tool, such as the bucket 34, such material can nevertheless be excavated through the open water with my method, as follows: Men in the working chamber will operate certain jets 47 by my novel method to be described presently, at the point in question at high pressures, and, in addition, use auxiliary tools horizontally as shown by dotted lines at 45, such as additional portable air and water jets, vibrating tools, rock drills, etc.; and if necessary, drive pipes horizontally along said lines, through which dynamite can be loaded and the ground loosened by a blast so that the material will be put in an unconsolidated state readily excavated by the bucket 34 operating through the water.

As will be described hereinafter, in connection with my free air or atmospheric working chamber, the jets shown at 47 can be used through my novel valve and stuffing box unit, so that all the horizontal work above described may be done through the inner wall 38, instead of below the edge 44. In addition the earth which is removed from the bottom of the working chamber 36 can be discharged through the skin wall 38 into the dredge wells 26, 27 and 28, by means of a mud pump or air lift operated from within the chamber by my said novel method to be described presently.

Since the air pressure in the working chamber 36 need only be sufficient to balance the hydrostatic head within the dredging wells 26, 27 and 28, it is obvious that by lowering the level of the water within the dredge wells of the caisson, the necessary air pressure in the working chamber may be reduced. This is of great advantage to the men in the work chamber as with the lower pressures men can work safely for longer periods. In addition, as has been mentioned above, there is a safe limit of 115 ft. of water or 50 lbs. per square inch air pressure under which men can work. Therefore the present compressed air method, as described in connection with Fig. 3, 75

6

has been limited to approximately this head. However, no such limitation exists with my method, for by placing a pump 48 with its discharge line 49 in a dredge well, the water level can be lowered to a lesser head 50, thereby reducing the necessary air pressure for this lesser head, while the external head 43 may be much greater than the limit head of 115 ft. Limitations to depths sunk with this form of my method are only functions of the capacity of the pumps used and the nature of the ground.

As can be seen, all methods known in the art of excavating can be used directly by the men in my cutting edge working chamber 36, in various combinations with all methods known in the art for open dredging through the dredging wells from the surface.

A comparison with the two present methods of open dredging or the compressed air method, as has been described in connection with Figs. 1, 2 and 3, shows in effect that my method involves the simultaneous use of open dredging and compressed air operation and therefore provides for the simultaneous advantages of both methods with none of their inherent disadvantages, as follows:

Men are able to work directly under the cutting edge and remove all material under the wall perimeter and thus effectively remove the force of bearing from inhibiting the sinking of the caisson as with the compressed air caisson of Fig. 3.

Because of direct access to the material it is possible to dig all hard materials no matter what their nature and thus keep proper line and grade by controlled digging at the spot, also an advantage of the compressed air caisson sinking of Fig. 3.

Because the working chamber is confined to the walled perimeter the uplift force of buoyancy is reduced to the minimum of the water displaced by the walled perimeter, and also since water can be pumped out of the dredging wells the buoyancy can be reduced still further to negligible amounts, now an advantage of open dredged caisson of Fig. 2.

Because the air pressure in the working chamber can be reduced by pumping in the dredging wells, the safe working depths for men under compressed air have been appreciably increased without increase in pressure through my invention and so presents this advantage.

Because material is pushed out of the work chamber into the dredging wells it is possible to excavate material from beneath the cutting edge without the tedious procedure of carrying the material through the muck locks, this important advantage now being obtainable only by the open dredging method of Fig. 2.

In general, my novel method possesses all the advantages of the compressed air caisson, and provides direct access to the material being excavated without the disadvantage of mucking through air locks, of greater uplift due to buoyancy caused by the air pressure, and without being limited to depths under which it can be used due to limitation of safe working pressures. I also provide in my novel method for all the advantages of the open dredged caisson of being able to reach greater depths, excavating directly through the water, reducing uplifts to a minimum and without its disadvantages of having no access to the cutting edge and the difficulty of digging hard consolidated materials through the water. In addition my method, because of the strategic location of the cutting edge working

chamber so as to give access to the material which directly creates bearing resistance, without inhibiting the space of the open dredge wells, provides advantages, indicated in the above general description, which no method used at present can provide.

To generally describe my free air or atmospheric cutting edge working chamber, and the methods involved in using it, I refer to Figs 6, 7 and 8, in which 51 indicates the outer caisson wall and hence the outer wall of the free air working chamber 36a. 52 is the inner wall of the caisson and also the internal wall of the working chamber. 53 is the roof of my free air cutting edge working chamber which at the same time is the bottom limit of the concrete walls 54, and 55 is the unique structural floor or bottom of my free air working chamber. As before, it can be seen that this working chamber 36a is confined to the perimeter of the caisson. The struts 21 are as before and likewise are the dredge wells 26, 27 and 28 which are left open to provide free access to the material removing devices. 56 is an access passageway for men and tools which communicates directly to the free air or atmosphere at the top of the caisson. It can therefore be seen that together with the access passageway 56 through the concrete walls 54 and the roof 53, the sides 51 and 52 and the floor 55, the working chamber 36a is a watertight enclosure with direct communication to the atmosphere. This chamber must, of course, be designed to withstand the pressure of the full hydrostatic head, wherefore I employ ribs to be described presently, which are of a size and spacing sufficient to withstand this pressure. The shape of this cutting edge working chamber 36a shown, is of course, not exclusive but is one of the numerous shapes that may be used depending on the type of the material through which the caisson is to sink and the depths and ultimate structures required.

With my atmospheric working chamber this construction excavation is performed as usual through the open dredge wells 26, 27 and 28, by means of the grab bucket 34 or other surface operated digging tool which will excavate through the water inside the dredge wells of the caisson. Men with their requisite tools enter the free air work chamber 36a directly from the surface by means of the access shaftway 56 without the necessity of an air lock since the work chamber is at atmospheric pressure. No material is dug within the confines of the work chamber since there is no open bottom as in my compressed air work chamber. Instead the material beneath the bottom 55 of the work chamber 36a is moved into the dredge wells 26, 27 and 28 to a location convenient to the grab bucket 34. Excavation, loosening and moving of the material by means of tools operated through watertight stuffing boxes and valves, details of which will be described hereinafter, in connection with Fig. 9. My novel stuffing boxes and valves will be so spaced along every foot of the perimeter of the free air working chamber 36a that by employing air and water jets, drills, dynamite, and other similar tools, and means through these stuffing boxes, the material can be efficiently washed and loosened into a state and location that the bucket will be able to excavate the material away from beneath the free air working chamber and permit the caisson to sink into the excavated area thus provided. These stuffing box and valve units are of such nature and size that the usual excavating tools of the type above mentioned can

work through them either horizontally or vertically, or diagonally, and in effect attack the material as efficiently as if the men who operate the tools from the free air work chamber 36a were in direct contact with such material. Since the men, however, operate in free air, the tremendous advantage is at once apparent of having men at the cutting edge, no matter what depth the caisson is to be sunk to, without having them subject to the inherent discomfort and dangers of compressed air, and still be able to perform all the functions previously performed only under compressed air, and at the same time to excavate and remove the material easily through the water by open dredging.

All the advantages described above for my compressed air cutting edge working chamber also apply to my free air cutting edge working chamber, over the methods heretofore used in the art of building and sinking a caisson, with the addition of being able to have men and tools operate in free air at a cutting edge subject to a hydrostatic head, which was never done before.

In Figs. 4, 6 and 8, at 57 I show by dotted lines, bulkheads which can be placed in both types of working chambers between the respective access shaftways. These bulkheads can be opened or closed by watertight doorways as desired, so as to cut off one section of the working chamber from another. This may often be desirable to concentrate excavation at a particular location or to control the buoyancy of the caisson by filling a particular chamber with water in order to rectify a tilt or shift in line and grade developed during sinking, or while setting a caisson on the river bottom during its initial placing at the site where it is to be sunk.

In connection with the process of floating a caisson in the water before setting it on the bottom in preparation for sinking through the earth, it should be noted both in the case of the compressed air and free air cutting edge working chamber that the buoyancy of my working chamber is at the lowest tip of the caisson, wherefore a caisson with such construction can often be floated into place with less displacement in depth than now is usual with open dredged caissons.

In Fig. 9 I show my free air cutting edge working chamber 36a in a larger scale, shown diagrammatically and more in detail. In this figure the parts hereinbefore mentioned are indicated by the same numerals. At 58 I show a walkway within the work chamber. The mentioned valve and stuffing box assemblies are indicated at 59 and 60.

Referring to the assembly indicated at 59, the numeral 61 represents a plug cock valve, or similar valve, which when open leaves the valve chamber completely clear and 62 is the handle by which the valve is opened or closed. Such valves are well known in this art. 63 is a pipe or casing which is threaded into the bottom flange of the valve 61 and welded to the floor 55 of the working chamber over an aperture thereon, so as to form the opening 64 of a diameter preferably equal to that of the pipe 63. Threaded to the upper flange of the valve 61 is a pipe or casing 65 of a size approximately equal to the free diameter of the valve 61 when fully open. Attached to the top of the pipe 65 is a watertight stuffing box 66 of a type used in all marine work and well known in this art. The stuffing box will allow a shaft or other similar device to pass through the same, enter the water at its outer end and yet be in the working chamber in

the dry at its other end. This combination of the valve 61, which is connected to the outside of the working chamber by means of the pipe 63, is the means by which my invention makes it possible to have men operate tools within the working chamber while the digging, drilling, setting, excavating, blasting, etc.; ends of the tools outside of the working may attack the material that is to be excavated.

The assembly at 59 shows an air drill being used through the valve 61 and stuffing box 66 to drill a hole 67 in the rock 68 beneath the working chamber while the similar assembly at 60 shows a pipe casing being used through the valve and stuffing box to load dynamite and blast the rock previously drilled by the air drill of the assembly 59. A brief description will illustrate the method by which these tools are used.

Referring now, again, to the assembly at 59, 69 is a high pressure air line connected to a manifold 70 which runs along the roof 53 inside the work chamber 36a and which, in turn, is connected to a surface compressor plant by means of the pipe line 71, brought to the working chamber from the surface through the access passageway 56. The valve 61 is normally kept in a closed position when it is not in use. The bit end 72 of the drill steel 73 is first inserted through the stuffing box 66 so that its tip passes through the stuffing box 66 into the casing 65.

In case the bit end 72 is over large, the stuffing box 66 can be disconnected from the casing 65, the shank end 73 inserted into the stuffing box from below and then the stuffing box reconnected to the casing 65 so the bit end 72 will enter the casing 65.

The high pressure air is then turned on by opening a respective valve on the manifold 70 which permits air to flow through the line 69 into the casing 65 where it is trapped by the stuffing box 66, at one end, and the normally closed valve 61 at the other. While the casing 65 is still under air pressure the valve 61 is opened by the lever 62. The air then rushes through the valve, the small pipeway 63, out through the opening 64 into the material beneath the working chamber 36a so as to provide a clear passageway for the tool to follow.

After the way is cleared, the air may be cut off, or left on, as conditions require, the drill steel is pushed through the valve 61 and the opening 64 into the material beneath the working chamber. The rock drill 74 is then attached to the shank end of the drill steel 73 and connected by means of the air hose 75 to the air manifold 70. The drill is now ready for use. Its tip or bit 72 is outside the working chamber and in the water saturated ground, while its shank 73 has passed through the watertight stuffing box and is connected in the dry to the drill 74 within the free air working chamber 36a. The drill can now be operated as it ordinarily is used when drilling through water. Assembly 59 shows the drill after having drilled the hole 67 in the rock 68.

Referring now to assembly 60, 76 is a pipe (shown in the drawing as for the loading and blasting of dynamite) which is passed through the stuffing box 65a, the casing 65a, the valve 61a, the short pipe 63a, and aperture 64a by the method outlined in the example of the drill steel used with assembly 59. 77 is a similar but smaller valve attached to the top of the pipe 76. This valve 77 is closed when the pipe 76 is passed through the stuffing box 66a.

Over the valve 77 is secured a pipe or casing 78

being similar to the casing 65a attached to the valve 61a, but, of course, also being of smaller dimensions. Casing 78 has connection to the compressed air manifold 70, as by the pipe line 79, and has a stuffing box 80 arranged at its upper end, said stuffing box, again, being similar to the stuffing box 66a but smaller in size.

After the pipe 76 is passed through the valve 61a and the bottom of the working chamber into the outer material, the respective valve for the compressed air line 79 is opened, as well as the valve 77, whereby the air will enter the pipe 76 and clear all possible obstructions out of the pipe, but discharging through pipe 76 into the material beneath its tip.

Now a special dynamite loading pipe 81 is prepared, the lower end 82 of which carrying the dynamite charge in an appropriate manner, as it is well known in this art. Pipe 76 will be lowered to the top of the hole 67a drilled in the material to be blasted.

The dynamite carrying pipe 81 will be passed through the stuffing box 80, casing or pipe 78, valve 77, and down through the pipe 76 into the hole 67a, as indicated in Fig. 9. The blasting wires 83 all the time are disconnected, but when the dynamite is in place, pipe 76 will somewhat be withdrawn while the dynamite carrying pipe 81 is held stationary so that only the comparatively light dynamite carrying pipe will be in the drilled hole 67a, whereupon the wire 83 will be connected to the exploder mechanism 84 and the dynamite exploded.

There are many occasions when it will be expedient to use pipe 76 as an exploratory pipe, following which exploration it would be convenient to operate a drill or jet through it. To do this, the end of stuffing box 80 is plugged, the valve 77 is opened, the air pressure is applied through the air line 79, and the pipe 76 is used for exploratory operations outside the working chamber, like an ordinary blow pipe, a device well known in underground operations. Then when the blow pipe locates an obstruction it can be left in place and the drill steel, or jet, or other tool, can be inserted through the stuffing box 80 and can be used passing through the blow pipe 76, as will be obvious from the description of similar operations hereinbefore.

It should be noted here that drill holes 85 and 86 are shown drilled on a slope, while the assemblies 59 and 60 indicate the operation of a tool vertically. As mentioned above, the valve and stuffing box assemblies are located along the free air cutting edge working chamber at a spacing to be determined so that the entire area beneath the working chamber can be reached by the probing tools operated from within. Some of these valve and stuffing box assemblies are therefore mounted vertically as at 59 and 60 in Fig. 9, some will be mounted horizontally, as indicated at 87 and some may be mounted at varying angles with the vertical, as for the sloping holes 85 and 86.

In Fig. 10 I illustrate how the whole valve, casing and stuffing box assembly may be mounted on a ball and socket joint in its connection to the wall or floor of the cutting edge chamber. Such a construction is most useful in a material where a great deal of angular work might be required. When using this construction the whole assembly, tool and all can be rotated to whatever angle is required without recourse to another valve and stuffing box unit. In said figure 61b is the valve, 65b the com-

11

pressed air casing, 66b the stuffing box, 64b is the opening in the floor 55 and 88 indicates in general the ball and socket joint for the valve, such valves being well known in this art. The dot and dash lines 89 and 90 indicate the center lines of the device at two angular positions.

In order that the men working within in my free air working chamber can see into the material outside of the same, a special valve and stuffing box unit may be used, as indicated in Fig. 11. The valve 61c first will be closed and the stuffing box earlier described will be removed from the top of the casing 65c. In its place a transparent glass plug 91 is secured into the casing 65c. The air pressure is then turned on by means of the air line 69c and the valve 61c is then opened by means of the lever handle 62c. The air stream will then enter the excavated area below the sight glass 91 and by using a powerful light 92, men in the working chamber will be able to view the exterior material by looking through the sight glass plug 91 and out through the opening 64c. In a modification of this operation a powerful light can be lowered through a blow pipe 76 arranged in a valve and stuffing box unit described, preferably of the ball and socket type, and thus a light is placed directly into the excavated area. When using this method the light 92 may be extinguished and an unobstructed view of the bottom can be obtained by using the viewing glass 91. As will be understood a light can also be permanently attached to such a pipe 76 thus forming a light pipe and used through a valve and stuffing box unit whenever the occasion demands.

From the above description it can be seen that my valve and stuffing box unit, as described, can have many combinations of uses, as it provides in one construction a positive waterproof cutoff to the outside, i. e. the closed valve, and a positive waterproof access opening to the outside, i. e. the open valve backed up by a compressed air casing and a stuffing box. It is clear therefore that by using water or air jets, drills, blow pipes, dynamite, glass plugs, light pipes, and other requisite devices, through my valve and stuffing box unit, it will be possible to move any material beneath the free air cutting edge working chamber into the dredge wells where it can easily be removed by a grab bucket or the like operated from the surface.

Referring once more to Fig. 9 the numeral 93 indicates a water pipe riser connected to jet pumps at the surface and 94 is a manifold along the roof 53 of the working chamber. Whenever a jet is to be used, a jet pipe with its proper nozzle is inserted through a stuffing box and valve unit, a hose connection made to the manifold 94, its valve opened by men in my free air work chamber and the jetting operation is carried on as desired, the men being able to view the results of their jetting at the spot by use of the sight glass 91 in combination with a light pipe inserted through a nearby valve and stuffing box unit. Such an operation is a tremendous advance in the art of jetting, because heretofore the jet pipe has always been shoved into the earth, and beneath the water where it was impossible for anyone to view the results of the operation. Because of the strategic location of my cutting edge working chamber, together with my flexible valve and stuffing box combination, it is possible for men to work in the comfort of normal atmospheric pressure and control the actions of a water jet by

12

actually looking at what is happening instead of guessing as has been the case heretofore.

In addition one of the basic troubles involved in jetting is easily avoided. When working in the earth a jet is always likely to become clogged at the nozzle end by the material in which it is immersed. Usually such jets are fixed to the caisson and when they are clogged, since they are inaccessible to cleaning at the nozzle end, they go out of service. With my method of inserting a short pipe through a valve and stuffing box unit, should a water or air jet become plugged, the jet pipe is withdrawn through said unit, the valve closed, the jet pipe pulled into the working chamber, and the plugged material removed from the nozzle end. When the jet pipe is thus cleaned it can be reinserted through the valve and stuffing box and put back into service. Very often when caissons are to be put through sticky clays or similar dense material, the use of jets is discarded because of the repeated experience of knowing they will become plugged in such material and thus be useless. With my method, jets, which are one of the most efficient means of moving any kind of material, are not subject to this often disqualifying objection.

It should be noticed also that a water jet as described hereinbefore, used in connection with an air blast emerging through one of my valve units forms the most explosive combination of air and water known in the art of jetting.

In Fig. 9 I also show, at 95, a riser pipe to the surface, and at 96 a manifold which, like the others, runs along the roof 53 of the cutting edge working chamber and around the entire perimeter of it. This riser is connected to a high powered sludge pump located at the surface. If desired the sludge pump can be operated from within the working chamber in which case it is directly connected to the manifold 96. Into this sludge pump is placed a mixture of slippery clay and water, such as bentonite, and this mixture is pumped down the access passage 56 through the riser 95 and into the manifold 96. 97 and 98 are flexible hose connections to the pipe ejectors 99 and 100. These pipes are inserted through two of my valve and stuffing box units, 101 and 102, as has been described. By opening the requisite valve on the manifold 96, the clay and water mixture 103 under pressure from the surface pump will flow through the hose lines 97 and 98 and into the ejector pipes 99 and 100, which are inserted through the stuffing box and valve units 101 and 102 into the material adjacent to the vertical side 51 of the caisson. Together with the air blast brought to these valve and stuffing box units through the hose lines 104 from the manifold 70, if required to loosen the original material next to the vertical side of the caisson, the ejector pipes can be efficiently used to deposit a layer of slippery clay 103 alongside the skin wall 51 of the caisson. Since these valve and stuffing box units may be spaced along the entire perimeter of the caisson, a uniform coating of this mixture can be placed in the original ground as the caisson passes through it. By using the sight glass plug 91, alone or in combination with a light pipe described hereinbefore, through a nearby stuffing box and valve unit, the progress of this clay depositing operation along the skin wall of the working chamber can be observed and controlled.

As the caisson sinks this slippery clay deposit remains in the original ground and thus the entire outer skin wall from top to bottom will

13

pass through, and always will be in contact with, the clay deposit 103. Such a deposit of slippery material on the outside of the caisson will reduce the skin friction to a negligible amount.

As discussed with the water jet, hereinbefore, the plugging of the ejector end of a sludge pump is very common, but when it is used combined with an air jet through my stuffing box and valve unit this difficulty can be eliminated.

It should be noted that if the access passageways 56 for men and materials were placed against the outer skin wall 51, as shown at 55a in Fig. 8, instead of in the center of the concrete wall 54, it is possible to place several of my valve and stuffing box units at different levels along these free air access shafts 56a. From these supplementary valve and stuffing box units, the results of the depositing of the clay at the working chamber level may be observed and any supplementary deposits of clay required can also be placed through the same in the manner described. This combination of free air cutting edge working chamber with its access to the outside through my novel combination of valve and stuffing box permits a positive method of depositing clay against the outer skin wall of a caisson to reduce to a minimum the skin frictions which inhibit the sinking of a caisson. The ejector pipes 99 and 100 may be moved, inwardly or outwardly, etc.; to aid in depositing of the clay.

I have shown how my novel methods and constructions provide positive means for bringing to the lowest minimums the three inhibiting forces against sinking, that is, the skin friction, buoyancy, and bearing under the cutting edge, a result which no other method used heretofore can show.

It should be noted that jets as indicated at 47 (Fig. 5) in connection with my compressed air cutting edge working chamber 36 may, of course, be operated through my valve and stuffing box units as shown in Fig. 9.

When the caisson is sunk to its final depth as required, usually a seal is made to the bottom strata. If the caisson is brought to rock, as is often the case, men working in the compressed air working chamber 36 (Fig. 5) can clear off all the loose material from the rock. Then concrete may be placed on the floor of the working chamber to create a seal to the rock between the outside water and material and the outer skin wall 37 of the compressed air working chamber. A foundation can be built under the caisson wall and, if required, the entire compressed air cutting edge working chamber 36 can be filled with concrete, the lock 42 removed and the shaftway 41 also filled with concrete. After the seal to the rock is made the dredge wells 26, 27 and 28 can be pumped out, and whatever structure is to be built within the confines of the caisson can be finished in the dry.

Should the bottom be some hard earth strata, as is sometimes the case, a seal to this bottom strata is likewise made, and the working chamber filled with concrete to provide a broad base to make the most efficient seal possible, the dredge wells pumped out and the internal structure finished in the dry.

With the free air cutting edge working chamber, when the caisson is brought to its final depth as shown in Fig. 9 by its close proximity to the rock ledge 106, the rock is leveled off by drilling and blasting as required through the valve and stuffing box assemblies 59 and 60. The rock is then cleaned by means of blow pipes and

14

jet pipes operating through my valve and stuffing box assemblies and then after the rock is leveled and cleaned, grout, concrete or other materials are ejected through the blow pipes operated through valve and stuffing box units. By moving the grout ejecting pipes in all directions as required, under control of operators working with blow pipes for sounding, and sight glasses combined with light pipes, the sealing materials can be placed so as to form a seal between the rock and the bottom 55 of the free air working chamber 36a, and at the same time provide a foundation for the caisson as well as a seal against the outside water and earth. The dredge wells 26, 27 and 28 can then be pumped clear of water and the final foundation finished as before, in the dry.

Should the final foundation require a type of open construction beneath the cutting edge, a section 107 of the bottom 55 (Fig. 9) can be made removable by disconnecting the bolts 108 which secure the removable bottom 107 ultimately to the sides 51 and 52. Air locks can be placed on tops of the access ways 56, compressed air introduced into the working chamber 36a before the bottom plate is removed, wherefore the bottom seal can be made under compressed air as described hereinbefore. Should the free air working chamber be of the bevel shape shown in Fig. 9, then horizontal or vertical sheeting 110, shown by dot and dash lines, can be carried down to rock and the final foundations finished as described for the compressed air cutting edge working chamber. In the process of reaching the rock, steel plate sheeting 111, previously attached to the wall of the free air working chamber, can be driven through a slotted stuffing box at 112 (built between the vertical reinforcing ribs 113 and sections of the floor 55 between them) down to the surface of the rock, and into it if required, with the help of jets and drills operating through my valve and stuffing box assemblies 59 and 60.

When the bottom of the free air cutting edge working chamber is founded on an earth stratum, grout or other materials, such as bentonite, can be ejected through valve and stuffing box assemblies to consolidate the bottom in the vicinity of the entire free air cutting edge chamber, and thus form the best possible foundation in the earth stratum. Following this the dredge wells can be unwatered and the interior foundations finished.

Very often, as in bridge foundations on earth strata, the dredge wells are not unwatered but the dredge wells are filled with concrete through the water by the tremie method. With my cutting edge working chamber, by constructing valve and stuffing box units of a proper size, concrete or other filling can be placed by pumping directly on the bottom without the necessity of using the tremie method.

If desired the free air cutting edge working chamber together with its access passageways can be filled with concrete after the seal to the bottom is made.

While the above descriptions have been confined to rectangular caissons sunk by their own weight during excavation, my cutting edge working chamber, both the compressed air and the atmospheric or free air type, can be used equally efficiently in large circular caissons which possess concrete filled walls to provide the weight for sinking. In fact the cutting edge working chamber can be made in any shape required, so as to follow the perimeter or contours of the caisson.

My free air cutting edge working chamber has a particular use in the sinking of smaller cylinders, constructed without concrete filled walls, and which are sunk into the ground by driving from the surface with a power hammer. Such a use, as will be described presently is to my knowledge, a most revolutionary and novel method for the sinking of small caissons (both cylindrical or rectangular) inasmuch as men and tools can have access to the material at the cutting edge while the driving hammer is operating at the surface, thus performing simultaneous sinking due to the driving force of the hammer and excavation due to the operation of the men and tools in the working chamber below.

Referring to Fig. 12, 114 is the caisson (cylindrical in this case) which is to be sunk by the power hammer 115. The blow of the hammer 115 is delivered to the cylinder 114 through the driving cap 116. 117 is my free air cutting edge chamber formed by the exterior skin wall 118 of the caisson and the interior wall 119 of the cutting edge working chamber (Fig. 13). 120 is the floor and 121 the roof of my free air working chamber. This working chamber is constructed to withstand external pressures and is braced and ribbed for strength similarly to the free air working chamber 36a described hereinbefore. 122 are valve and stuffing box units of the type described. 123 is an access passageway from the surface to the working chamber 117. 125 is a driving cylinder of exactly the same size as the cylinder 114, and which joins it at a bearing connection 126, flanked by the splice plates 127, so arranged that the blow of the hammer 115 will be transmitted through the cap 116 and the driving cylinder 125 to the caisson 114 which is to be driven into the ground. This driving cylinder is constructed so as to allow the men and tools to enter within the caisson 114 and pass through the access shaftway 123 to reach the working chamber 117 below. To achieve this an access hole 124 is arranged in the driving cylinder 125 so as to provide a connection between the exterior and the interior as described. 128 is a pipeway through which the excavated material is removed and may be formed at the bottom by the interior wall 119 of the free air cutting edge chamber 117. The pipeway 128 passes through the driving cylinder 125 in a similar manner to that shown by the opening 124 for the access passageway 123. Splice connections between the upper and lower ends of the respective sections of the access passageway 123 and the exhaust pipeway 128 will be made as shown at 126 for the caisson 114. These splices do not in any way carry the blow from the hammer 115, it is delivered only through the wall of the driving cylinder 125 to the wall of the caisson 114. Hose connections for delivering high pressure air for the excavating tools in the working chamber, water lines for jetting, and pipeways for delivering clay and water mixtures to the working chamber, electric power lines, etc., can be carried down within the access passageway 123, if the access passageway is large enough, or externally as shown in the section of Fig. 13. In said section 130 is a high pressure air line, 131 a water line for jetting, 132 is a pipe line for clay and water, and 133 is a conduit for electric power lines. These lines are brought through the driving cylinder in the manner described hereinbefore.

Sinking of the cylinder is performed as follows:

The hammer 115 transmits its blow through the driving cap 116, the driving cylinder 125, to the caisson 114, causing the bottom tip 134 of the cutting edge to move vertically through the ground. As the caisson moves into the ground the material beneath the cutting edge will develop bearing resistance to counteract the driving, and the material along the vertical sides will develop skin friction which will also cause a force counteracting the driving. To remove these two forces, men with their tools enter the access passageway 123 through the opening 124 and descend to the cutting edge working chamber 117. By means of valve and stuffing box units 135 and the pipe line 132 connected to the sludge pump on the surface, slippery clay and water mixture can be ejected into the material along the vertical sides of the caisson 114 by the methods described, thus decreasing the frictional resistance. Compressors and jet pumps at the surface deliver air and water under pressure to manifolds in the working chamber 117 through the pipe lines 130 and 131. By methods already described, using my valve and stuffing box units 122 for the air and water jets, the material inside the caisson cylinder 114 can be loosened and put in a saturated state. Since the tip 134 of the caisson is driven into the material alongside and beneath the cutting edge working chamber 117 the water and material will rise through the exhaust passageway 128 which provides an exitway with the least resistance. In effect by ejecting air and water into the passageway 128 at its lower end, an air lift is formed which will carry the water and earth in solution up through said exhaust passageway for discharge above the surface. While this will be the most usual method for removing the material loosened and placed in saturation by the men operating the requisite tools through the valve and stuffing box units in the working chamber, any other means of moving this excavated material from the base of the working chamber can be used. For example, a sludge pump 136 can be lowered down through the pipeway 128 and the material agitated by the men operating in the working chamber 117 can be pumped directly to the surface for disposal. Other means such as orange peel buckets, bailing buckets, endless belt excavators, etc., can be used to remove the material excavated by the men in the free air working chamber. The pipeway 128 can be omitted if desired, and the inside of the caisson 114 will then become the exhaust chamber for removing the excavated material. The pipeway 128, or its equivalent, in effect becomes a dredge well similar in use to the dredge wells 26, 27 and 28 mentioned hereinbefore and therefore all the operations already described in connection with my cutting edge working chambers can be similarly performed and the material similarly removed. However, the nature of the restricted area of the pipeway 128 presents the opportunity of using an airlift in connection with jetting air and water through the valve and stuffing box units 122, which is one of the most convenient methods of excavating earth known in the art.

Thus by excavating, as described, the material beneath the free air cutting edge working chamber 117 is removed, the bearing resistance decreased, and the cylinder can be driven through the ground by the action of the hammer 115. Should boulders be encountered, they can be drilled and blasted through my valve and stuffing box units and thus pulverized for removal.

When the final strata is reached, which in the case of the smaller cylinders is usually rock, the bottom is cleared of loose material, leveled off, the cylinder driven to bearing on the rock, and a grout seal placed within the cylindrical caisson on top of the rock to make a water cut off. The caisson can then be unwatered and filled with concrete if (as is usual) it is to form a foundation pier, or following unwatering any structure can be built in free air inside the caisson. The free air working chamber can be removed if desired before placing the concrete fill, or can itself be filled with concrete and left within the permanent foundation. Thus all operations of driving, excavating, reducing skin friction by claying up the sides, sealing the bottom, and building the final foundation, can be done with my free air cutting edge chamber equipped with my valve and stuffing box units.

What I claim as new and want to protect by 20 Letters Patent of the United States, is:

In an underground closed working chamber, the combination of, a normally closed valve secured on the wall of the working chamber at the inside thereof, said valve being adapted to be opened and then provide a passage from the inside of the working chamber to the outside, a casing secured on said valve, connected to a source of compressed air and adapted to communicate with said valve, and therethrough to the outside when the valve is open, an opening being provided in said casing opposite to the opening of said valve, a stuffing box in the opening of said casing adapted to permit a sealing sliding of a desired elongated instrument therethrough, means to control the entrance of compressed air into said casing, whereby the compressed air may be shut off from said casing and said instrument partly inserted through said stuffing box thereinto, then the valve opened and 40 the compressed air permitted to pass into said

casing and through said valve to the outside, and then the instrument advanced through the stuffing box, the casing and the valve to the outside, said instrument having an inner controlling end portion projecting from the stuffing box, said instrument being in the form of a pipe passed through said stuffing box, said casing and said valve, from the inside of the working chamber to the outside thereof, a second normally closed valve secured on the inner end of said pipe, a second casing connected in a controlled manner to a source of compressed air on said second valve having a co-axial opening therewith, and a second stuffing box in said co-axial opening adapted to permit an elongated second instrument to sealingly slide through said second stuffing box, through said second casing, and through said second valve, and through said pipe to the outside under an outward air pressure.

CHARLES GOODMAN.
